AUTOMATIC ELECTRIC STARTER FOR BURNERS

Filed Aug. 5, 1948

FIG. 1.

UNITED STATES PATENT OFFICE

2,512,250

AUTOMATIC ELECTRIC STARTER FOR
BURNERS

Pablo Jakob, Buenos Aires, Argentina

Application August 5, 1948, Serial No. 42,653
In Argentina August 23, 1947

5 Claims. (Cl. 219—39)

1

The present invention is concerned with an automatic electric starter for burners with automatic gasifiers.

Up to the present, the problem of starting the gasifying unit to function, has been solved by means of sundry devices, but none of them have given completely satisfactory results.

As is known, the problem to be solved, is to provide sufficient heat to cause the initial gasification of a liquid combustible, and after that has been accomplished, the start of the combustion, leaving to the action of the combustion, once started, the continuity of the process.

The new invention solves, with a maximum of structural and constructional simplicity, the problems inherent to such an operation.

It is composed substantially of a starter button which is used to put into action an electric resistance linked up with the gasifying tube, and at the same time close the outlet valve of the combustible. As also a thermostat element regulated in such a manner, that when the gasifying tube reaches a prefixed temperature, it acts on a relay, which also, simultaneously, opens the outlet valve of the combustible and cuts the supply of current to the aforementioned heating element.

One of the principal advantages of this device consists in the fact that the only thing necessary to start the burner working is to press the starter button. As, from there on, until the burner is working normally, the intervening stages succeed each other automatically.

Another notable advantage arises from the system of the use of an electric resistance as a means of heating. The operation takes place in the best possible conditions as regards cleanliness and efficiency as well as the degree of homogeneity required. As the electric current is cut off immediately the burner starts to function properly, the procedure is also extremely economical.

The thermostat element, regulated as required, guarantees the temperature required for the gasifying tube at the moment that combustion is commenced.

The formation of matter foreign to the normal process of combustion, which with the continued use of the burner accumulates and in time may be the origin of trouble in the functioning of the same, is eliminated by the new procedure.

The entire device is of simple and solid construction and economical to produce, as can be seen from the drawings which accompany the present memorandum and claims. They illustrate one of the preferred forms for the practi-

2

cal realization of the fundamental idea, which, of course, as is logical could be altered.

I refer to the drawings in the following description, with the object of enlarging on and clarifying the idea, and at the same time demonstrating its practicability.

Figure 1 is a complete plan of the automatic starter device.

Figure 2 is a partial view of the zone corresponding to the starter button and the relay as also their auxiliary elements.

In the corresponding description use will be made of numbers to identify the distinct parts of the whole, it being understood that the same numbers although in different styles, indicate the same thing or their equivalents.

The starter button 1 which can slide longitudinally in the interior of the guide 2 of the fixed element 3 has an extension 4 which has a hooked end 5 which can be hooked to the corresponding hooked end 6 of the spring arm 7 of the element 8 which is fixed in 9.

A lug 10 of the extension 4 has an opening 11 in which is attached the end 12 of the spring 13 the opposite end of which 14 is attached in its turn, to the opening 15 at the end 16 of the cross strut 17.

The cross strut 17 which is rigid with the stem 18 has at its other end 19 a slot 20 which takes, with the use of the washer 21 and the split pin 22 the pivot pin 23 attached to the end 24 of the iron core 25 of the relay 26, the coil of which 27 is secured by its yoke 28.

The core 25 has its end free 29, and a contiguous collar surrounded by insulating tape 30 and has also a pivot pin 31 which with the use of the washer 33 and the cotter pin 32 is connected through the slot 34 with the end 35 of the cross piece 36 which has its opposite end free 37. This cross strut 36 kept in its place by the washer 38 and the split pin 39 revolves on the pivot pin 40, mounting the piece pivotally on the fixed element 41.

The gasifying tube 42 is surrounded by the electric resistance 43 which is enveloped in an adequate packing 44. The gasifying tube 42 has an internally threaded end 45 which is connected to the outlet valve 46 of the combustible. This valve 46 is united to the intake pipe 47 of the combustible which has its outlet in a valve chamber 48 which has at one end the ejector orifice 49. Facing this orifice 49 is the stopper needle 50 which is constituted by the end of the stem 18, the latter having a wider outside portion with a threaded member 51 which is in contact

with the tapped inner wall 52 of the chamber 48. A packing or gland ensures 53 that the chamber is hermetically sealed.

A metal ring 54 which surrounds the piece 46 is united by means of the screws 55 to the bimetal plate 56.

The electric circuit of the resistance 43 is composed of the conductors 57 and 58, resistance 43, conductors 59 and 60, contacts 61 and 62 and conductor 63.

The circuit of the relay, in its turn is composed of the conductors 57 and 64, the bobbin 27, conductor 65, spark extinguisher 66, conductor 67, plate 68 with its contact 69, contact 70 of the plate 71, conductor 60, contacts 61 and 62 and conductor 63.

The plate 71 has a screw 72 with a head 73 made of glass.

The functioning of the automatic electric starter is as follows.

Pressing the starter button 1 (Figure 1) it descends (the special references refer to the distribution in the figures) until the end 5 hooks on the end 6 of the element 8. The lug 10 has drawn down with it, the end 12 of the spring 13 the opposite end of which 14 makes the cross strut 17 revolve in a clockwise direction.

The oscillation of the cross strut 17 on the one hand forces the stem 13 to revolve on its axis and on the other hand raises the iron core 25 of the relay 26. When the stem 13 revolves the threaded wider portion 51 (Figure 1) in contact with the tapped internal wall 52 of the chamber 48 forces the stopper needle 50 to approach the ejector orifice 49, and blocks it. At the same time, when the iron core 25 of the relay 26 is raised its lower end 29 establishes contact between the plates 61 and 62, as appears in both figures.

The circuit corresponding to the resistance 43 is thus closed, and as a result of this, begins to heat the gasifying tube 42. The thermal condition of the latter is partially transmitted to the elements 49 and 54, and thus, of course, also the bimetal plate 56, which warps, due to the action of the temperature. It is fixed in such a manner that it now makes contact with the glass head 73 of the screw 72 of the plate 71, uniting the contacts 70 and 69 when the temperature of the gasifier 42 has reached the required degree.

When the contacts 70 and 69 unite, they close the circuit corresponding to the coil of the relay, which causes the descent of its iron core and the positioning of the insulating collar 30 between the contacts 61 and 62. On that occurring the following things happen. The circuits corresponding to the resistance 43 and to the coil 27 of the relay, open, by breaking the electric contact between 61 and 62: the cross strut 17 revolves in a counterclockwise direction, placing tension on the spring 13 and simultaneously making the stem 13 revolve, by which the action of the threaded wider portion 51 on the tapped inner wall 52 of the chamber 48 makes the stopper needle 50 with its wider portion 51 recede and allows the combustible to pass through the ejector orifice 49, and simultaneously revolves the cross strut 36 (also in a counterclockwise direction) and its free end 37 pushes the spring arm 7 of the element 8, unhooking the ends 6 and 5 upon which, the starter button, having been released, returns to its normal position, forced by the tension of the spring 13.

Thus the burner is made to function and at the same time the mechanism of the automatic

electric starter has returned to its initial position, also in its turn ready to repeat the cycle of its operation, just as has been described.

It is desired to make it quite clear that the foregoing description is a preferred form of the invention, not limited, but merely demonstrative and as an example.

Any number of changes or modifications in the construction and/or details may be introduced, without exceeding the limits of the invention, which are clearly specified in the claims that follow.

Having now fully described my invention, I claim:

1. An automatic starter for an oil burner adapted for use with gasifiable oils, including the combination of a heated oil gasifier; a valve casing connected to the gasifier; an electric heater adjacent to the latter for thermally gasifying oil passing through said gasifier; a fuel supply pipe connected to the valve casing; a movable valve member extending into said valve casing in a position to close the flow of oil from said fuel supply pipe to the gasifier when moved in one direction and in the opposite direction effective to open the flow of oil thereto; an operating member for moving the valve member; an electric circuit connected to the electric heater having a pair of corresponding contacts for opening and closing said circuit and adapted to be connected to a current source; a movable circuit closer for closing the circuit through the two contacts in one position and opening the circuit in another position thereof; a manually operated member for simultaneously moving the operating member and thereby the valve member to control the flow of oil to the gasifier and moving the circuit closer to close the circuit through said contacts and energize said electric heater and thereby heat said gasifier; and means for restoring said circuit closer to open circuit position and simultaneously moving said operating member to initial position upon said gasifier attaining a predetermined high temperature by means of said electric heater.

2. An automatic starter for an oil burner adapted for use with gasifiable oils including the combination of a heated oil gasifier; a valve casing connected to the gasifier; an electric heater adjacent to the latter for thermally gasifying oil passing through said gasifier; a fuel supply pipe connected to the valve casing; a movable valve member extending into said valve casing in a position to close the flow of oil from said fuel supply pipe to the gasifier when moved in one direction and in the opposite direction effective to open the flow of oil thereto; an operating member for moving the valve member; an electric circuit connected to the electric heater having a pair of corresponding contacts for opening and closing said circuit and adapted to be connected to a current source; a movable circuit closer for closing the circuit through the two contacts in one position and opening the circuit in another position thereof; a manually operated member for simultaneously moving the operating member and thereby the valve member to control the flow of oil to the gasifier and moving the circuit closer to close the circuit through said contacts and energize said electric heater and thereby heat said gasifier; and electrically operated means for automatically restoring said circuit closer to open circuit position and simultaneously moving said operating member to initial position upon said gasifier at-

taining a predetermined high temperature by means of said electric heater.

3. An automatic starter for an oil burner adapted for use with gasifiable oils, including the combination of a heated oil gasifier; a valve casing connected to the gasifier; an electric heater adjacent to the latter for thermally gassifying oil passing through said gasifier; a fuel supply pipe connected to the valve casing; a movable valve member extending into said valve casing in a position to close the flow of oil from said fuel supply pipe to the gasifier when moved in one direction and in the opposite direction effective to open the flow of oil thereto; the valve casing having an internally threaded portion and the valve member having a corresponding threaded portion engaging with the internally threaded portion in said valve casing and being partly rotatable therein to provide the opening and closing movement of said valve member; a lever mounted on said valve member for partly rotating same; an electric circuit connected to the electric heater having a pair of corresponding contacts for opening and closing said circuit and adapted to be connected to a current source; a movable circuit closer for closing the circuit in one position thereof; means for pivotally connecting one end of said lever to said movable circuit closer; a manually operated member connected to the other end of said lever for simultaneously moving said circuit closer to close said circuit through said contacts and partly rotating said valve member for controlling the flow of oil to said gasifier; and automatically operated electrical means for disabling said operating member and restoring the same and the partly rotatable valve member and also the movable closure member to initial position upon said gasifier and valve casing attaining a predetermined high temperature by means of said electric heater.

4. An automatic starter for an oil burner adapted for use with gasifiable oils, including the combination of a heated oil gasifier; a valve casing connected to the gasifier; an electric heater adjacent to the latter for thermally gassifying oil passing through said gasifier; a fuel supply pipe connected to the valve casing; a movable valve member extending into said valve casing in a position to close the flow of oil from said fuel supply pipe to the gasifier when moved in one direction and in the opposite direction effective to open the flow of oil thereto; the valve casing having an internally threaded portion and the valve member having a corresponding threaded portion engaging with the internally threaded portion in said valve casing and being partly rotatable therein to provide the opening and closing movement of said valve member; a lever mounted on said valve member for partly rotating same; an electric circuit connected to the electric heater having a pair of corresponding contacts for opening and closing said circuit and adapted to be connected to a current source; a movable circuit closer for closing the circuit through the contacts in one position and opening the circuit in another position thereof; means for pivotally connecting one end of said lever to said movable circuit closer; a movable core directly connected to the circuit closer; a stationary solenoid for actuating the core and electrically connected to said circuit contacts; a manually depressible member having a spring connecting the latter with the other end of said lever for simultaneously moving said circuit closer to close said circuit through said contacts and partly rotating said valve member for controlling the flow of oil to said gasifier; a branch circuit having a second pair of corresponding contacts normally spaced apart in open circuit position and connected in series with the first mentioned corresponding pair of contacts; a thermostatic member connected to said valve casing in effective position to become distorted upon being heated and depress said insulator whereby to close said second pair of contacts and energize said solenoid through said branch circuit when the gasifier and valve casing have attained a sufficiently high predetermined temperature to distort said thermostatic member; a second lever pivotally mounted adjacent to said core and having one end connected thereto; a first hook fixed on said

other end of said lever for simultaneously moving said circuit closer to close said circuit through said contacts and partly rotating said valve member for controlling the flow of oil to said gasifier; a branch circuit having a second pair of corresponding contacts normally spaced apart in open circuit position and connected in series with the first mentioned corresponding pair of contacts; an insulator disposed on one or the second pair of contacts; a thermostatic member connected to said valve casing in effective position to become distorted upon being heated and depress said insulator whereby to close said second pair of contacts and energize said solenoid through said branch circuit when the gasifier and valve casing have attained a sufficiently high predetermined temperature to distort said thermostatic member; and automatically operated means for disabling the manually depressible member and allowing the same to return to initial position upon said solenoid being energized.

5. An automatic starter for an oil burner adapted for use with gasifiable oils, including the combination of a heated oil gasifier; a valve casing connected to the gasifier; an electric heater adjacent to the latter for thermally gassifying oil passing through said gasifier; a fuel supply pipe connected to the valve casing; a movable valve member extending into said valve casing in a position to close the flow of oil from said fuel supply pipe to the gasifier when moved in one direction and in the opposite direction effective to open the flow of oil thereto; the valve casing having an internally threaded portion and the valve member having a corresponding threaded portion engaging with the internally threaded portion in said valve casing and being partly rotatable therein to provide the opening and closing movement of said valve member; a lever mounted on said valve member for partly rotating same; an electric circuit connected to the electric heater having a pair of corresponding contacts for opening and closing said circuit and adapted to be connected to a current source; a movable circuit closer for closing the circuit through the contacts in one position and opening the circuit in another position thereof; means for pivotally connecting one end of said lever to said movable circuit closer; a movable core directly connected to the circuit closer; a stationary solenoid for actuating the core and electrically connected to said circuit contacts; a manually depressible member having a spring connecting the latter with the other end of said lever for simultaneously moving said circuit closer to close said circuit through said contacts and partly rotating said valve member for controlling the flow of oil to said gasifier; a branch circuit having a second pair of corresponding contacts normally spaced apart in open circuit position and connected in series with the first mentioned corresponding pair of contacts; a thermostatic member connected to said valve casing in effective position to become distorted upon being heated and depress said insulator whereby to close said second pair of contacts and energize said solenoid through said branch circuit when the gasifier and valve casing have attained a sufficiently high predetermined temperature to distort said thermostatic member; a second lever pivotally mounted adjacent to said core and having one end connected thereto; a first hook fixed on said

manually depressible member; a second hook fixed in stationary position at one end and disposed in effective position to engage with the first hook upon depression of said manually depressible member and retain the latter in depressed position; and an extension on the second hook disposed adjacent to the other end of said second lever in effective position to allow said other end of said second lever to displace said extension when the solenoid is energized 10 and thereby disengage said second hook from said first hook and allow said spring to return said manually depressible member to initial position.
